UNITED STATES PATENT OFFICE.

JOHN WEBSTER, OF EAST PROVIDENCE, RHODE ISLAND.

DESIGN FOR A HAIR-BRUSH.

42,597.

Specification for Design.

Patented June 4, 1912.

Application filed September 1, 1910. Serial No. 580,143. Term of patent 14 years.

To all whom it may concern:

Be it known that I, JOHN WEBSTER, a citizen of the United States, residing at East Providence, in the county of Providence and State of Rhode Island, have invented a new, original, and ornamental Design for Hair-Brushes, of which the following is a specification, reference being had to the accompanying drawing, forming part thereof, in which—

Figure 1 is a perspective view showing the shape or configuration of the brush embodying my design. Fig. 2 is a side elevation thereof. Fig. 3 is an end elevation thereof.

The design consists in the shape of the brush considered as an entirety.

I claim—

The ornamental design for a hair brush as shown and described.

JOHN WEBSTER.
